COMBINED MOTOR UNIT AND BASE FOR A FOOD BLENDER

Jack Morgan, Chicago, Ill.

Application October 1, 1952, Serial No. 21,667

Term of patent 14 years

(Cl. D89—1)

Fig. 1

Fig. 2

Fig. 3

To all whom it may concern:

Be it known that I, Jack Morgan, whose full and correct name is Jack Morgan, a citizen of the United States, residing in the city of Chicago, county of Cook, and State of Illinois, have invented a new, original, and ornamental Design for a Combined Motor Unit and Base for a Food Blender, of which the following is a specification, reference being had to the accompanying drawing, forming a part thereof.

Fig. 1 is a side elevational view of a combined motor unit and base for a food blender showing my new design;

Fig. 2 is a top plan view thereof; and
Fig. 3 is a bottom view thereof.

The sides not shown are substantially like the side shown in Fig. 1.

I claim:

The ornamental design for a combined motor unit and base for a food blender, as shown and described.
